G. W. CASSIDY

ATTACHMENT FOR BRIDGE ARM LAMPS

Filed March 11, 1924

George W. Cassidy
Inventor

By his Attorneys, Dodgeon & Rae

UNITED STATES PATENT OFFICE.

GEORGE W. CASSIDY, OF NEW YORK, N. Y.

DESIGN FOR AN ATTACHMENT FOR BRIDGE ARM LAMPS.

Application filed March 11, 1924. Serial No. 8,900. Term of patent 3½ years.

To all whom it may concern:

Be it known that I, GEORGE W. CASSIDY, a citizen of the United States, residing in the city, county, and State of New York, have invented a new, original, and ornamental Design for Attachment for Bridge Arm Lamps, of which the following description, in connection with the accompanying drawing, is a specification.

The drawing shows in full lines, what the invention really is, and in dotted lines, the application of the device of the invention to a bridge arm lamp.

The design itself consists of a cord and

tassel mounted on an extension arm all being arranged so that the cord and tassel hang parallel with the main standard of the lamp and from the top thereof, and on the side directly opposite to the bridge arm.

The drawing is a side elevation of the attachment for bridge arm lamps showing my design.

I claim:

The ornamental design for an attachment for bridge arm lamps substantially as shown and described.

GEORGE W. CASSIDY.
